UNITED STATES PATENT OFFICE.

PHILIP L. GOODMAN, OF CHICAGO, ILLINOIS.

GARBAGE REDUCER AND DISTILLATOR

1,419,135.

Specification of Letters Patent. Patented June 13, 1922.

Application filed November 6, 1920. Serial No. 422,207.

To all whom it may concern:

Be it known that I, PHILIP L. GOODMAN, a citizen of the United States, and a resident of Chicago, Cook County, and State 5 of Illinois, have invented certain new and useful Improvements in Garbage Reducers and Distillators, of which the following is declared to be a full, clear, and exact description.

10 This invention relates to apparatus for the reduction and distillation of garbage and industrial waste, and its principal object is to provide improved apparatus for accomplishing this result in a more efficient manner than has been done heretofore. Another object is to provide means whereby derivatives from garbage may be separated and collected in separate receptacles. Another object is to provide a reducer and distillator 15 for garbage and industrial waste wherein the greases, phosphoric acid, ammonia, alcohol, base, tar product and gas may be separated from the mass by the direct application of furnace heat to a retort-distillator 20 containing the mass, the residue reduced in the retort-distillator to carbon, and the carbon deposited in the combustion chamber of the furnace and utilized as fuel for the reduction and distillation of garbage, and 25 reduced to ash, from which potash and fertilizer is obtained. Another object is to produce a reducer and distillator for garbage and industrial waste which is a time saver, is economical in operation, both in the saving of fuel and in the number of workmen 30 necessary to operate the plant. Another object is to provide an apparatus which is continuous in operation and requires only ordinary and occasional attention.

40 With these and other objects in view, this invention consists of a retort-distillator for the reception of garbage and a condenser pipe in which the volatile substance are carried off from the retort-distillator, and in 45 which they are condensed at different places along the length of the pipe, whereby they may be collected in separate receptacles, the retort-distillator being removably supported in the combustion chamber of a furnace, 50 whereby after the process of distillation therein, the residue may be readily discharged from the retort-distillator into the combustion chamber for use as fuel and for further reduction.

55 The invention further consists in the sev-

eral novel features hereinafter fully set forth and claimed.

The invention is clearly illustrated in the accompanying drawing, in which:—

Fig. 1 is a view partly in elevation and partly in cross section of a garbage reducer and distillator embodying a simple form of the preferred invention; Fig. 2 is a detail, central, vertical section through the dome and coupling of the retort-distillator; Fig. 3 is a detail, vertical section of a fragment of the retort-distillator showing a form of clamping means used for removably securing the dome or head of the retort-distillator to its receptacle, and Fig. 4 is a longitudinal section taken on the line 4—4 of Fig. 1.

Referring to said drawing, the reference character 5 designates a furnace or incinerator of suitable construction, having a fire 75 box 6 and a combustion chamber 7 that may be separated from the fire box by a wall or baffle 8 around which the products of combustion pass from the fire box to the combustion chamber. Grate bars 9 are provided in said fire box and combustion chamber as usual, and an arch 10 incloses the upper end of the furnace. A roof 11 may be provided above said arch as shown, and a smoke stack 12 is provided to carry off 80 products of combustion. The exact form of furnace or incinerator herein shown and described is not material to this invention, broadly considered, but serves well for the purpose of illustration.

In the roof 11 and arch 10 are holes 13 which open to the combustion chamber 7 and the roof is reinforced around said holes by the flanged rings 14. Removably supported by the roof are the retort-distillators 95 15 which are of sufficient length to extend well into the interior of the combustion chamber. Said retort-distillators may be provided with horizontal flanges 16, adapted to rest on the rings 14.

100 Each retort-distillator comprises a garbage receptacle 17 which may be in the form of an elongated kettle, closed at the top by a dome or head 18 which is removably secured thereto. Conveniently, the dome or 105 head may be clamped to the receptacle by a plurality of clamp screws 19 threaded in arms 20 that are rotatively secured in up-standing lugs 21 formed on the flange 16 of the receptacle. The dome has an annular 110

flange 22 on its lower end that rests on the flange 16 of the receptacle 17 or on an interposed asbestos gasket 23, and the clamp screws are adapted to bear against said flange 22 to clamp the dome and receptacle together.

Connected to the dome of each retort-distillator is a condenser pipe 24 which may have a flexible branch pipe 25, which connects with the dome by a short nipple 26 (see Figs. 2 and 4) screwed into dome, and a pipe coupling 27. A shut-off valve 25^a is interposed between each branch pipe and the condenser pipe to control the passage in each branch pipe. This arrangement permits each retort-distillator to be readily disconnected from the condenser pipe 24 while the process of reduction and distillation is being carried on. Said pipe 24 is exposed to the atmosphere and has a plurality of traps or U bends 28, 29, therein, from which lead discharge pipes 30, 31, that empty into tanks or receivers 32, 33. Beyond the last trap or U bend 29 the condenser pipe is inclined upwardly and extends through a water jacket 34, and its end portion 36 is carried into the furnace and terminates in a nozzle 37 which may be located in the fire box or combustion chamber. Cold water is supplied to the water jacket 34 through a water supply pipe 38 and discharged therefrom through a water discharge pipe 39.

In accordance with one phase of the invention, a fluid collecting pipe 40 is let into the retort distillator, which pipe has a plurality of inlet branches 41 along its length. The upper end of said pipe 40 opens into the discharge opening of the dome and may be removably supported therein by a pin 42 which may be inserted through holes in the nipple 25 and pipe 40. Said pipe may, however, be long enough to rest on the bottom of the garbage receptacle and protrude into the discharge opening of the dome.

In the operation of the apparatus above described the domes are removed from the garbage receptacles, the latter filled or partially filled with garbage or industrial waste, the domes replaced and clamped on the receptacles and the condenser pipe 24 coupled to the domes. At the initial stage, fuel is employed in the fire box, which fuel is ignited and the products of combustion therewith pass around the retort-distillators and escape through the smoke stack. A temperature of from 600 to 1200 degrees Fahrenheit is maintained in the combustion chamber, to which the garbage or industrial waste in the retort-distillator is subjected.

A process of distillation then takes place, causing the various derivatives to flow through the pipe 24 and discharge into the tanks or receivers 32, 33, those of greater specific gravity flowing into the tank 32 and

those of less specific gravity flowing into the tank 33. The vapors and volatile substances that flow past the traps 28, 29, are finally condensed by the cold water contained in the water jacket 34 and flow back through the inclined pipe into the trap 29 and discharge through the pipe 31 into the tank 33.

Upon the cessation of the flow of liquids a process of carbonization takes place in the retort-distillators, leaving a mass of live carbon in each, and a gas making stage is arrived at, the gas given off being of such quality as to take the place of or in addition to other fuel for the continuation of and completion of all the final processes. Afterwards the residual carbon is removed from the retort-distillators and turned into the combustion chamber 7 where the carbon is now used as fuel for carrying on the process of distillation, and is converted into an ash, which ash is subjected to a certain process (which forms no part of this invention) to extract the potassium salts contained therein, and the residue is then subjected to further treatment by which there is produced a complete and finished fertilizer, containing phosphoric acid, ammonia and potash.

To remove the carbon from any retort-distillator, the shut-off valve 25^a, in the branch pipe 25 leading from it is closed, and the retort-distillator is disconnected from the branch pipe, lifted out of the combustion chamber, the dome removed, the receptacle inverted over the hole 14, and the carbon contents discharged upon the grate bars of the combustion chamber, where it is subjected to the products of combustion issuing from the fuel in the fire box, and to the gas coming from the gas pipe. Combustion of the carbon then takes place and supplies the heat for the further distillation of garbage. After the receptacle has been emptied it is refilled, closed, replaced in the combustion chamber, and connected up to the branch pipe, and the shut-off valve is opened, and the process of distillation is continued in that retort-distillator.

The combustion chamber receives the carbon produced in each retort-distillator after all the distillates are driven off and the carbon takes the place of other fuel to further generate the heat necessary to operate in the reduction of waste and garbage placed into the several retort distillators. The residual ash obtained from the combustion chamber after it is again subjected to a further process becomes a finished fertilizer from which the greater portion of the potassium salts are extracted.

In the apparatus herein illustrated and described, approximately 1000 pounds of garbage is acted upon in each retort-distillator, and about 250 pounds of coal are used as the fuel at the commencement of

the operation of the furnace. Thereafter, until shut down, the carbon and combustible gases from the retort-distillators are used as fuel for the reduction and distillation of garbage. From each 1000 pounds of garbage about 100 pounds of carbon is obtained and with a plurality of retort-distillators in operation, this amount from each retort-distillator, together with the gas obtained, is sufficient to carry on the processes indefinitely. Obviously additional fuel may be supplied in the fire box to make up for any deficiency.

The products derived from organic waste, garbage and industrial waste are grease, phosphoric acid, ammonia, alcohol base, potash, tar product and gas, and the remainder is a finished fertilizer.

In this discovery all of the valuable contents are extracted which heretofore were lost, the only products by other methods being the greases and tankage. This left considerable waste matter to be disposed of by dumping or other methods which are expensive. The salvage of valuable by-products and the economical methods of complete disposal without the attendant expense of disposal, of filter cloths, corn cobs and unburned vegetable matter, makes this invention of value greater than those of others now existant.

The distillation and retorting by direct heat and the simultaneous production and distillation of the various products by this economical method described are processes superior to any now in use, and the fact that there is positively no disagreeable odor or smoke exuding from or by this device or chimney makes this the most hygienic method of disposal known.

By the use of the apparatus described, a great saving of time for the complete reduction and distillation of garbage is had, and practically all of the waste matter is made use of, there being little or nothing to be otherwise disposed of.

I claim as new, and desire to secure by Letters Patent:

1. A reducer and distillator for garbage and waste matter, comprising a furnace, a plurality of retort-distillators removably supported in the combustion chamber of the furnace, each being separately removable from the furnace at any time, and a condenser pipe leading from each retort-distillator.
  2. A reducer and distillator for garbage and waste matter, comprising a furnace, a plurality of retort-distillators extending through holes in the top wall of the furnace and removably supported in the combustion
- chamber of the furnace, said retort-distillators being separately removable from the furnace and each having a removable dome and a condenser pipe removably connected to said dome.
3. A reducer and distillator for garbage and waste matter, comprising a furnace, a retort-distillator removably supported in the combustion chamber of the furnace and having a removable dome provided with a discharge opening, a fluid collecting pipe removably supported in said retort-distillator and discharging into said discharge opening and a condenser pipe leading from the discharge opening of the dome of said retort-distillator.
4. A reducer and distillator for garbage and waste matter, comprising a furnace, a plurality of retort-distillators, removably supported in the combustion chamber of the furnace, and each having a removable dome, and a discharge opening in said dome for the discharge of vapors, and each retort-distillator being removable and invertible, whereby the carbonized contents thereof may be deposited in the combustion chamber, for use as fuel for carrying on the reduction and distillation process.
5. A reducer and distillator for garbage and waste matter, comprising a furnace having a plurality of holes in one wall, a plurality of retort-distillators extending in through said holes and removably supported in the combustion chamber of the furnace, and each having a removable dome, and a discharge opening in said dome for the discharge of vapors, and each retort-distillator being removable and invertible over its hole in the furnace wall, whereby the carbonized contents thereof may be deposited in the combustion chamber, for use as fuel for carrying on the reduction and distillation process.
6. A reducer and distillator for garbage and waste matter, comprising a furnace, a plurality of retort-distillators removably supported in the combustion chamber of the furnace, and each having a removable dome, and a discharge opening in said dome for the discharge of vapors, a condenser pipe, valve controlled branch pipes leading therefrom to the several retort-distillators, and each retort-distillator being definitely located and separately removable at any time and invertible, whereby the carbonized contents thereof may be deposited in the combustion chamber, for use as fuel for carrying on the reduction and distillation process.

PHILIP L. GOODMAN.
